UNITED STATES PATENT OFFICE.

CLINTON D. TABOR, OF HUNTINGTON, NEW YORK, ASSIGNOR OF ONE-HALF TO
HERMAN I. SORENSEN, OF NEW YORK, N. Y.

SASH CENTER.

Application filed February 15, 1921. Serial No. 445,139.

To all whom it may concern:

Be it known that I, CLINTON D. TABOR, a citizen of the United States, residing in Huntington, in the county of Suffolk, Long Island, New York, have invented new and useful Improvements in Sash Centers, of which the following is a specification.

This invention relates to window fixtures which are commonly known as sash centers or pivots and which are designed for pivotally mounting a sash in a window frame so that the sash may be turned or rotated into an open and closed position.

One of the objects of this invention is the production of a pivot fixture of this character which necessitates removing less wood from the sash rail and thus permits of using the same on window sashes having lighter rails than those heretofore used for this purpose. Another object of this invention is to provide a tension device in which the spring may be constructed of flat spring metal which is not liable to become broken in use and can be easily replaced at low cost. A still further object of this invention is to so organize the sash center that the same will still be in an operative condition even though the dog or locking bar is broken into two adjacent to the axis of the sash center.

In the accompanying drawings:

Figure 1 is a fragmentary elevation of the sill and sash of a window equipped with my invention. Figures 2 and 3 are horizontal sections taken on line 2—3, Fig. 1, and looking downwardly and upwardly, respectively. Figure 4 is a vertical longitudinal section of the sash center and adjacent parts of the sill and sash embodying my improvements. Figures 5, 6 and 7 are vertical transverse sections taken on the correspondingly numbered lines in Fig. 4. Figures 8, 9, 10 and 11 are perspective views of the important elements of the sash center.

Similar characters of reference refer to like parts throughout the several views.

Although the sash center may be installed so as to permit a sash to turn in any desired direction in the frame, the same, for example, is shown in the drawings interposed between the sill or lower horizontal member 20 of a window frame and the lower horizontal bar or rail 21 of a sash. Between these relatively stationary and rotatable window members my improved sash center

is mounted, the same being constructed as follows:

22, 23 represent two attaching plates one of which is secured to the sash bar or rail and the other to the frame bar or sill so that one may be turned relatively to the other. In this instance both of the plates 22 and 23 are arranged in a recess 24 in the underside of the sash bar and the plate 22 is fixed and secured to the sash rail by means of screws 25 and the plate 23 is rotatable and secured to the frame sill by means of screws 26. The plate 22 serves as a guide for a locking bar or dog 27 which is movable into and out of locking engagement with the plate 23 and for convenience the plates 22 and 23 will be hereafter referred to as guide plates and locking plates respectively. The locking plate 23 has its central part dished inwardly so as to form an outer chamber or recess 28 on its outer side and on its margin the same is provided with longitudinal and transverse flanges 29, 30 which project inwardly and form a chamber 31 on the inner side of the guide plate. The central part of the guide plate forming the bottom of the outer chamber 28 is provided with a pivot or bearing opening 32 and around the latter, this bottom is provided with a plurality of guide openings 33 which are preferably four in number and arranged equidistant. The transverse flanges 30 of the guide plate are somewhat higher or project inwardly farther than the longitudinal flanges 29 and each of these transverse flanges is provided with a guide notch or recess 34.

The locking plate 23 rests with its inner face against the edges of the longitudinal flanges of the guide plate while its opposite transverse edges are arranged adjacent to the inner side of the transverse flanges 29. On the central part of the locking plate the same is provided with an inwardly projecting tubular hub or pivot sleeve 35 which projects the pivot or bearing opening 32 of the guide plate and forms the axis or fulcrum about which the guide and locking plates of the sash center revolve one relatively to the other. On its inner face the locking plate is provided with a plurality of locking grooves, recesses or notches 36, 37, 38 which radiate from the pivot sleeve or hub 35 and are preferably arranged at three different angles relatively to each

other, although, if desired, more or less may be employed to suit different conditions or requirements. As shown, the locking grooves 36 are arranged lengthwise of the locking plate, the grooves 37 are arranged transversely and the grooves 38 obliquely and the same are adapted to co-operate with the locking bar to hold the sash in its full closed, full open and partly open positions. 5

10 The locking bar 27 has a wide central part 39 arranged between the guide and locking plates and provided with a central guide opening 40 which receives the pivot sleeve or hub 35 and the opposite ends 41 of the locking bar are reduced in width and engage with the guide notches 34 in the transverse flanges of the guide plate, whereby the locking bar is guided in movement parallel with the axis about which the locking 15 and guide plates turn relatively to one another, but the locking bar is held against rotation. On that side of the locking bar facing the guide plate the same is provided with four tension pins or projections 42 which extend outwardly through the guide openings 33 and on its opposite side facing the locking plate, this bar is provided with a longitudinal locking rib or tongue 43 which is adapted to engage with one or another set of locking recesses 36, 37 and 38 20 in the locking plate. Within the outer chamber 28 is arranged a tension spring 44 which is preferably made of flexible metal and of square form and engages its margin 25 with the outer ends of the tension pins 42 at different points circumferentially of the spring. The locking plate, locking bar and guide plate are held in an assembled position but perform their respective movements 30 and functions by means of a coupling bolt 45 which extends transversely through the tubular hub or pivot sleeve and also through an opening 46 in the center of the tension spring and bears with its head 47 against 40 the outer side of the locking plate while its screw nut 48 bears against the outer side 45 of the tension spring.

When the sash is closed the tension of the spring holds the ribs of the locking bar firmly in engagement with the longitudinal grooves 36 of the locking plate and thus holds the sash yieldingly in this position. Upon applying sufficient pressure to the sash to turn the same out of its normal 50 closed position and overcome the tension of the spring, the co-operating wedge action of the longitudinal grooves 36 in the locking plate and the rib of the locking bar causes the latter to be deflected sufficiently 55 to disengage these ribs and grooves and hold the same out of engagement until the sash has been turned half open at which time the oblique locking grooves of the locking plate will be in line with the locking ribs 60 and permit the latter to be pressed into the

same by the resilience of the spring. Upon now continuing the opening turning movement of the sash until the same is fully opened the locking bar will be first disengaged from the oblique locking grooves and 70 then permitted to spring back into the transverse grooves of the locking plate. In like manner the closing turning movement of the sash will first cause the locking bar to be first disengaged from the respective 75 grooves of the locking plate and then engaged successively with the other locking notches of the locking plate until the sash is shut. During this movement of the sash the locking bar moves parallel with the axis 80 about which the sash turns, the movement in one direction being produced by the wedge action of the locking ribs and grooves and the movement in the opposite direction by the resilience of the spring. 85

By constructing the spring of a piece of flat metal in the manner shown the thickness of the fixture as a whole can be materially reduced and thus reduce the depth of the recess which has to be cut into the sash to receive the same, thereby enabling the fixture to be applied to a sash having comparatively narrow rails. 90

Owing to the square formation of the spring and the engagement of the same at a plurality of points around the axis of the fixture by the tension pins of the locking bar, the resilience of all parts of this spring are brought into play, inasmuch as the spring is dished slightly while being flexed 100 and the strain distributed over the several bearing points thereby permitting of using a spring of much smaller area and also lighter weight than otherwise would be necessary to secure the same amount of tension. 105

Furthermore, in the construction this locking plate and guide plate turn one directly upon the other by means of the pivot hub so that the locking bar is entirely independent of these plates and free to perform the sole function of locking the plates in whatever position they may be left. Owing to this construction, if at any time the locking dog should break in two at the middle, the pieces of the same would still be confined between the plates and perform their locking function inasmuch as the spring would still bear against the tension pins of these pieces and hold the latter in their operative position. 115

I claim as my invention:

1. A sash center comprising two plates adapted to be attached to the frame and sash of a window, respectively, one of said plates having a bearing opening and the other having a hub journaled directly in said bearing opening, and one of said plates being provided with a series of grooves arranged at different angles, a locking bar arranged between said plates, and a spring for holding 120 125 130

said locking bar yieldingly in engagement with one or another of said grooves.

2. A sash center comprising two plates pivoted directly one upon the other and adapted to be attached respectively, to the frame and sash of a window, one of said plates having flanges provided with notches, and the other plate being provided with locking grooves arranged at different angles, 10 a locking bar guided at its end in said notches and provided with a locking rib, and a spring for moving said bar in the direction for engaging its ribs with said grooves.

15 3. A sash center comprising two plates adapted to be attached, respectively, to the frame and sash of a window, and said plates being directly pivotally connected with each other, one of said plates having a plurality 20 of locking grooves arranged at different angles, a locking bar adapted to engage said grooves, and a tension spring engaging said locking bar at different points around the pivotal connection between said plates.

25 4. A sash center comprising two plates adapted to be attached to the frame and sash of a window, one of said plates having a bearing opening, and the other a pivot hub engaging with said bearing opening and 30 also a plurality of locking grooves arranged at different angles, a locking bar provided with a locking rib adapted to engage with one or another of said grooves and having a plurality of tension pins arranged around 35 said hub, a flat spring engaging different parts of the margin with said pins, and a bolt connecting said spring with the plate having said locking grooves.

5. A sash center comprising two plates adapted to be attached to the frame and sash 40 of a window, one of said plates having a bearing opening, and the other a pivot hub engaging with said bearing opening and also a plurality of locking grooves arranged at 45 different angles, a locking bar provided with a locking rib adapted to engage with one or another of said grooves and having a plurality of tension pins arranged around said hub, a flat spring engaging different parts of the margin with said pins, and a 50 bolt arranged axially in said hub and connecting the spring with the plate having said hub and grooves.

6. A sash center comprising two plates adapted to be connected respectively with 55 the frame and sash of a window, one of said plates having an inwardly dished outer chamber, the bottom of which is provided with a central bearing opening and a plurality of guide openings arranged around said bearing opening, and the other plate being provided with a pivot hub which is journaled in said bearing opening and a plurality of locking grooves which are arranged 60 at different angles, a locking bar arranged between said plates and provided with a rib adapted to engage with one or another of said grooves and also with a plurality of tension pins projecting through said guide 65 openings, a flat metal spring arranged in 70 said outer chamber and engaging different parts of its margin with the ends of said pins, and a bolt arranged in said hub and connecting the central part of said spring with the plate having said hub.

CLINTON D. TABOR.
